UNITED STATES PATENT OFFICE.

JOSEPH BECKER, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

COKE-OVEN STRUCTURE.

1,404,336.

Specification of Letters Patent. Patented Jan. 24, 1922.

Application filed January 26, 1920. Serial No. 354,176.

To all whom it may concern:

Be it known that I, JOSEPH BECKER, a citizen of the United States, residing in Pittsburgh, in the county of Allegheny and State 5 of Pennsylvania, have invented a new and useful Improvement in Coke-Oven Structures, of which the following is a specification.

This invention relates generally to coke 10 oven structures and has for its essential object the provision of individual protective covers for the individual jamb bricks, of which are constructed the jambs that face the end of the heating walls of the oven battery. The 15 jambs are often exposed to jars, blows and other rough usage, in the operation of the coke oven doors, and from other causes; the invention not only effectively protects the jambs against damage but also leaves the 20 joints, between the individual jamb bricks, readily accessible so that these joints may be pointed up, whenever necessary, without removing the coverings from the jamb bricks.

The invention includes among its objects 25 such other improvements or advantages in construction and operation as are found to obtain in the structures and devices hereinafter described or claimed.

In the accompanying drawings, forming 30 a part of this specification, and showing for the purpose of exemplification, a preferred form and manner in which the invention may be embodied and practiced, and without limiting the claims of the invention 35 specifically to such illustrative instance or instances:—

Figure 1 is a fragmentary side elevation of a coke oven structure provided with the improvements of the present invention.

40 Figure 2 is a horizontal sectional view of the same, taken in a plane indicated by the line 2—2 of Figure 1.

Figure 3 is a top plan view of a jamb brick employed in the construction of the 45 jambs at the end of a heating wall and showing a fragmentary horizontal section of the coke oven door co-operating therewith.

Figure 4 is a front elevation of a number 50 of jamb bricks, such as illustrated in Figure 3.

Figure 5 is a vertical sectional elevation taken in a plane indicated by the line 5—5 of Figure 4.

Figure 6 is a top plan view of the jamb 55 bricks employed in the construction of that

portion of the jambs where the peep-hole is located.

Figure 7 is a front elevation of the construction illustrated in Figure 6.

The same characters of reference indicate 60 the same parts throughout the several views.

In its present embodiment, the invention is incorporated in a coke oven battery of the by-product type, and for convenience the present description will be confined to 65 this use of the invention. The features of the invention are, however, readily susceptible of other uses, for example, in connection with coke oven batteries of other form; hence, it is manifest that the scope of the invention is by no means confined to the specific use and specific embodiment herein described. 70

Referring to the drawings:

There is shown a fragment of a coke oven 75 battery of the by-product type, which embodies in its construction a plurality of coking chambers 11 arranged side by side, and having the usual crosswise extending alternating heating walls 12 intermediate adjacent coking chambers, as shown in Figure 2, 80 said heating walls being provided with the usual vertical flame-flues 13 for generating heat to coke the charges of coal in the coking chambers 11. The heating walls 12 extend vertically to the top 14 of the coke oven battery, said top being of the usual construction, and facing the end of each heating wall 12 is a jamb 15 consisting essentially of a vertical wall section substantially co-extending along the end of the heating wall and formed of jamb bricks, as will be hereinafter described. The outer face of each jamb 15 is braced by a pair of vertical buckstays 16 which extend vertically beyond the top 14 of the coke oven battery. As stated, the heating walls 12 extend crosswise of the coke oven battery and their opposite ends are also placed with jambs such as are indicated at 15, and vertical buckstays are also provided for bracing the outer faces of the jambs on that side of the battery opposite to that indicated on the drawing. 90

In accordance with the usual practice, the 105 heating walls 12 are constructed of liner-brick, sections 16 and 17, connected together at intervals by tie-brick sections 18, and the flame-flues 13 are located between the several tie-brick sections, as shown. The several 110

sections constituting each heating wall are constructed of silica brick, whereas the jambs 15 facing the ends of the heating wall are constructed of clay bricks. As a result 5 of the facts that the heating walls and the adjoining jambs are formed of materials having different co-efficients of expansion, that the jambs are exposed exteriorly to radiation and that the buckstays exert variable pressures upon the jamb bricks during 10 expansion or contraction of the battery, the joints between the several bricks forming a jamb frequently open up, so that it is necessary to point up these joints in order 15 to preserve gas-tight conditions at the end of each heating wall.

The mouth of each coking chamber is closed by a coke oven door 19 consisting essentially of a metallic outer shell 20 and 20 the usual internal refractory lining 21 supported by said outer shell. As shown in Figs. 2 and 3, the outer shell 20 is formed with opposite vertically extending shoulders 22 adapted to rest against the reverse shoulders 23 of the jambs at the opposite sides of the mouth of the coking chamber. When in closed position, the door 19 projects within the coking chamber 11 beyond the shoulders 23 of the jambs; and when a charge in 25 a coking chamber has been coked the doors of such chamber are opened or removed and the finished coke is pushed out of the chamber and disposed of in the usual way. The operation of removing and replacing the 30 doors is necessary every time a charge of coal has been coked in a coking chamber, and this operation is frequently liable to cause damage to the jamb bricks by knocking of the door against them when removing or replacing the door.

According to the present invention, individual protective covers are provided with the individual jamb bricks of each jamb, whereby the jambs are not only protected 45 from damage but the joints between the bricks may also be reached whenever it becomes necessary to point up these joints, without removing the covers. Each jamb is constructed mainly of a plurality of bricks 50 24 of the general form illustrated in Figs. 3 to 5 inclusive, said bricks respectively having vertically-extending shoulders 25 formed in their opposite side faces and a continuous horizontal groove 26 extending around the front face 27 of and connecting the shoulder 25 on the opposite sides of each brick. The bricks 24 are laid one upon the other to 55 form the jamb, and the horizontal joints between them are filled with a suitable binding material. At the tier of each jamb where the peep-hole 28, for inspecting the horizontal flue of the heating wall, is located, two companion jamb bricks 29 are employed instead of one. The outside faces 30 of the 60 jamb bricks 29 are similar to the analogous

faces of a jamb brick 24 and each brick is provided with a continuous horizontal groove 31 extending from the shoulder 25 of the outside face 30 around the front face 32 and terminating at a vertical groove 33 70 located at the junction of the front face 32 and the inside face 34 of each brick 29. As shown in Figs. 6 and 7, the inside faces 34 of the pair of bricks 29 are spaced from each other and between them is positioned a filler 75 brick 35 lower in height than the jamb bricks 29 to leave the peep-hole 28 which extends through the jamb. The vertical joints between the jamb bricks 29 and the filler brick 35 are filled with a suitable binder, as well as the horizontal joints between the three 80 bricks just mentioned and the jamb brick 24 beneath them. Each of the jamb bricks 24 is protected by a cover 36, preferably formed of metal, and having wings 37 extending from the front face of the cover along the side faces of the jamb brick. At their inner ends the wings 37 of the cover are provided with shoulders 38 fitting the companion shoulders 25 of a jamb brick; and projecting 85 from the inner faces of the plate 36 is a continuous horizontal tongue 39 that enters the groove 26 of the jamb brick to hold the cover firmly in place on the front and side faces of the jamb brick. The jamb bricks 29 are also 90 provided with covers 40 extending over their front and outside faces, said cover having shoulders 41 fitting with shoulder 25 of the jamb bricks 29 and a continuous tongue 42 that enters the groove 31 of the jamb 95 bricks 29. At their ends adjacent to the vertical grooves 33 the covers 40 are provided with vertical flanges 43 which enter 100 said grooves.

With the above construction the individual 105 jamb bricks constituting a jamb 15 are adequately protected by individual covers extending over their front and side faces, so that damage to the jamb bricks from any cause is to a large extent eliminated. The 110 shoulders 38 of the jamb brick covers 36 and the analogous shoulders 41 of the jamb brick covers 40 constitute the vertical shoulder 23 of the jamb, that receives the impact of the coke oven door. The joints between the 115 bricks are at all times accessible and may be maintained in perfect condition without removing a single cover from a jamb brick.

The invention as hereinabove set forth is embodied in a particular form of construction but may be variously embodied within the scope of the claims hereinafter made.

I claim:

1. In a coke oven structure, in combination: a heating wall; a jamb facing the end 125 of said heating wall, said jamb composed of individual bricks having vertically extending shoulders formed in their side faces and a groove extending around their side and front faces; and individual covers for the 130

- individual jamb bricks, said covers respectively having a front face positioned in front of the front face of a brick; wings extending along the side faces of the latter, 5 the wings terminating in shoulders fitting the aforesaid shoulders of the jamb brick, and a tongue extending inwardly from the front face and wings for interlocking engagement with the aforesaid groove of a 10 jamb brick; substantially as specified.
2. In a coke oven structure, in combination: a heating wall; a jamb facing the end of said heating wall, said jamb being composed of individual jamb bricks provided 15 with grooves; and individual covers for the individual bricks having tongues adapted to interlock with said grooves, while leaving the joints between individual bricks exposed; substantially as specified.
- 20 3. In a coke oven structure, in combination: a heating wall; a jamb facing the end of said heating wall and composed of a plurality of individual jamb bricks; and individual covers interlocked with and extending 25 over the exposed faces of said individual
- bricks, while leaving the joints between individual bricks exposed; substantially as specified.
4. In a coke oven structure, in combination: a heating wall; a jamb facing the end 30 of said heating wall and composed of a plurality of individual jamb bricks; and individual covers supported by and extending over the exposed faces of said individual 35 bricks, while leaving the joints between individual bricks exposed; substantially as specified.
5. In a coke oven structure, in combination: a heating wall; a jamb facing the end 40 of said heating wall and composed of a plurality of individual bricks having exposed front and side faces; and individual protective plates covering the exposed faces of said individual bricks, while leaving the joints between individual bricks exposed; substan- 45 tially as specified.

In testimony whereof I have hereunto set my hand.

JOSEPH BECKER.
